(57) **CLAIM**

The ornamental design for a pet feeder as shown and described.

DESCRIPTION

FIG. 1 is a top, front, left perspective view of a pet feeder showing my new design;

FIG. 2 is bottom, rear, right perspective view thereof;

FIG. 3 is a top, front, right perspective view thereof;

FIG. 4 is a front elevation view thereof;

FIG. 5 a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a top, front, left perspective view of the pet feeder where the pet feeder is in a configuration of use; and,

FIG. 11 is an enlarged view of detail “11”, identified in FIG.

5.

The dash-dash broken lines in FIG. 10 depict an environment that form no part of the claimed design. In the drawings, the broken lines depict portions of the pet feeder that form no part of the claimed design.
